UNITED STATES PATENT OFFICE.

ANTON F. NORDENSKJOLD, OF PITTSBURGH, PENNSYLVANIA, ASSIGNOR TO UNITED FOUNDRY & MACHINE COMPANY, OF McDONALD, PENNSYLVANIA.

FLUID-OPERATED JACK.

Application filed September 2, 1924. Serial No. 735,278.

To all whom it may concern:

Be it known that I, ANTON F. NORDENSKJOLD, a citizen of the United States, residing at Pittsburgh, in the county of Allegheny and State of Pennsylvania, have invented certain new and useful Improvements in Fluid-Operated Jacks, of which the following is a specification.

My invention relates to fluid operated jacks, and while primarily intended for use in connection with motor vehicles, it is obvious that the device may be employed for any purposes wherein it is found to be applicable.

Important objects of the invention are to provide a fluid operated lifting apparatus for motor vehicles, which is permanently secured to and carried by the motor vehicle; which is power operated and valve controlled to elevate either the entire vehicle, or any end, side or wheel thereof; which is so disposed on the motor vehicle as to be out of the way normally and to be brought into service when required without difficulty; which includes an automatically regulated fluid distributing mechanism permitting of the continued operation of the latter after the elevating members have reached their maximum extension without liability of damage to any parts of the structure; and which may be conveniently suited for installation to any type of motor vehicle without requiring any additional materials except that incorporated in the invention.

Further objects of the invention are to provide a device of the character stated, in a manner as hereinafter set forth which will facilitate and expedite the elevating operation; which may be operated from the driver's seat; which is simple in its construction and arrangement, strong, durable and efficient in its use, compact, attractive in appearance and comparatively inexpensive to manufacture, install and operate.

With the foregoing and other objects in view which will appear as the description proceeds, the invention resides in the combination and arrangement of parts and in the details of construction hereinafter described and claimed, it being understood that changes in the precise embodiment of

the invention hereinafter disclosed can be made within the scope of what is claimed without departing from the spirit of the invention.

In the drawing forming a portion of this specification and wherein like numerals of reference designate corresponding parts throughout the several views:

Figure 1 is a top plan view of a lifting apparatus for motor vehicles in accordance with my invention.

Figure 2 is a sectional view of the control valve showing the relative positions of the parts thereof during the lowering operation.

Figure 3 is a similar view of the control valve showing the relative positions of the parts thereof during the elevating operation.

Figure 4 is a side view of the elevating mechanism attached in position to the axle of the motor vehicle.

Figure 5 is a fragmentary sectional view of the cylinders and associated parts.

Figure 6 is a sectional view on line VI—VI, Figure 5.

Referring in detail to the drawing there is shown in Figure 1, four elevating mechanisms, respectively, indicated at 1, 2, 3, and 4. The elevating mechanisms 1 and 2 are carried by the front axle 5, of the motor vehicle, and are disposed adjacent to respective vehicle wheels A and B. The elevating mechanisms 3 and 4 are carried by the rear axle 6, of the motor vehicle and are disposed adjacent to respective vehicle wheels C and D. Each of the elevating mechanisms 1, 2, 3 and 4 is rigidly secured to respective vehicle axles 5 and 6 by a clamping element 7, as clearly shown in Figure 4, of the drawing or in any other suitable manner.

The elevating mechanisms 1, 2, 3 and 4 are identical in construction and each includes a cylinder 8 and a cylinder 9 the former extending longitudinally forward of the axle on which it is mounted and the latter extending longitudinally rearward therefrom. The cylinder 8 is provided with an associated longitudinally aligned guide member 10 disposed rearwardly of the vehicle axle

on which it is mounted, and the cylinder 9 is provided with an associated longitudinally aligned guide member 11 disposed forwardly of the vehicle axle. In other words, the 6 guide member 11 extends parallel with and is disposed along the outer side of the cylinder 8, while the guide member 10 extends parallel with and is disposed along the inner side of the cylinder 9.

10 The cylinders 8 and 9 and the associated guide members 10 and 11 are preferably constructed as integral casting, and the bores 12 of the former are separated from the guideways 13 of the latter by the transversely disposed partitions 14. The adjacent ends of the bores 12 of a pair of cylinders 8 and 9 are provided with an intercommunicating port 12' for the purpose to be described. The other end of each of the 20 cylinders 8 and 9 is closed by a cap 10' formed with a centrally disposed threaded aperture 11'. Each of the partitions 14 is formed with a centrally disposed aperture 15 and with a stuffing box 16, the latter being formed in the side of the partition 14 that faces the guideways 13.

15 A plunger 17 is mounted in the bore 12 of each of the cylinders 8 and 9 and is connected to one end of a plunger rod 18 which 30 extends slidably through the aperture 15 of the partition 14. The other end of the plunger rod 18 is connected to the guide block 19 which latter is shiftably mounted in the guideway 13 of each of the guide members 10 and 11. The guideways 13 are rectangular in transverse cross section and the guide blocks 19 shiftably mounted therein are likewise rectangular in transverse cross section for the purpose of preventing 35 the rotation of the latter in the guideways 13.

40 A follower 20 provided with a laterally disposed adjusting leg 21, is mounted on the plunger 18 and engages in the stuffing box 16 to compress the packing 22 therein to prevent leakage during the operation of the plunger rod 18 in the partition aperture 15. The leg 21 extends through an opening 23 in the guide member 10, 11 and is adjusted by means of the bolt 24 which extends therethrough and threadably engages in the laterally disposed boss 25, as clearly shown in Figure 5, of the drawing.

45 Each of the guide members 10 and 11 is provided with a longitudinally extending slot 26, which is formed on the lower wall thereof adjacent to the cylinder 8, 9 along the side of which it is disposed, so that the slot 26 of one guide member will be longitudinally aligned, as nearly as possible with the slot 26 of the other guide member.

50 Each of the elevating mechanisms 1, 2, 3 and 4 further includes a pair of toggle bars 27, 28. The upper end of the bar 27 extends through the slot 26 and is pivotally

55 connected to the guide block 19, mounted in the guide member 11, by means of a bearing pin 29 and the upper end of the bar 28 is similarly connected to the guide block 19 mounted in the guide member 10. The 70 lower ends of the toggle bars 27 and 28 are pivotally connected to the foot 30 by a common pivot pin 31. As the upper ends of the bars 27 and 28 are pivotally connected to respective guide blocks 19 in opposed guide 75 members 10 and 11, the movement of the guide blocks 19 toward each other will act to distend the bars 27 and 28 whereby they will exert an endwise pressure which increases as the bars approach a vertical position, while the movement of the guide blocks 19 in a direction away from each other will act to collapse the bars 27 and 28 against the motor vehicle frame structure. 80

85 An operating fluid reservoir 32 is fixedly supported in any suitable manner to the frame structure of the motor vehicle, and a fluid pressure pump 33 is likewise fixed to the latter in any suitable manner and position to permit of the operation of the motor vehicle engine to drive and operate the fluid pump 33.

90 A four way valve element 34, consisting of the valve casing 35 and the valve 36, is carried by the motor vehicle and is preferably located to permit of its manipulation from the operator's seat. The valve casing 35 is provided with four ports 37, 38, 39 and 40 and the valve 36 is provided with a pair of communicating ports 41 and 42 and with a pair of communicating ports 43 and 44. A fluid supply pipe 45 connects the pump 33 with the valve casing port 39, and a fluid return pipe 46 connects the valve casing port 37 with the fluid reservoir 32. An intake pipe 47 connects the reservoir 32 with the pump 33. A relief valve 48 for the purpose hereinafter stated, is mounted in the supply pipe 45 and is connected to the intake pipe 47 by the relief pipe 49. 100

105 Ports 12' of elevating mechanism 1 and 3 are connected by the common elevating conduit 50 and the ports 12' of the elevating mechanisms 2 and 4 are connected by a similar elevating conduit 51. A common lowering conduit 52 is connected as indicated at 53, in each of the apertures 11' of the cylinders 8 and 9 of the elevating mechanism 1, and in each of the apertures 11' of the cylinders 8 and 9 of the elevating mechanism 3. A similar lowering conduit 54 is connected as indicated at 55, in each of the apertures 11' of the cylinders 8 and 9 of the elevating mechanism 2 and in each of the apertures 11' of the cylinders 8 and 9 of the elevating mechanism 4. 110

115 The elevating conduits 50 and 51 communicate with each other through the cross connection 56 which latter connects with the 120

125

130

valve casing port 38 by the pipe 57. The lowering conduits 52 and 54 communicate with each other through the cross connection 58, which latter connects with the valve casing port 40 by the pipe 59.

One end of the cross connection 56 communicates with the elevating conduit 50 at a point intermediate of a pair of control valves 60 and 61 mounted in the conduit 50, and the other end of the cross connection 56 communicates with the elevating conduit 51 at a point intermediate of a pair of control valves 62 and 63 mounted in the conduit 51. One end of the cross connection 58 communicates with the lowering conduit 52 at a point intermediate of a pair of contact valves 64 and 65 mounted in the conduit 52, and the other end of the cross connection 58 communicates with the lowering conduit 54 at a point intermediate of a pair of control valves 66 and 67 mounted in the conduit.

In practice the operation of the device is as follows:—Assuming that the device is in the inoperative position and it is desired to operate all of the elevating mechanisms 1, 2, 3, and 4 to elevate the entire vehicle, all of the control valves 60, 61, 62, 63, 64, 65, 66 and 67 are opened, and the valve element 34 is regulated to bring the valve ports 41, 42, 43, and 44 into registration with respective valve casing ports 38, 39, 40 and 37, as clearly shown in Figure 3 of the drawing.

The pump 33 is now operated by its connection with the operating motor vehicle engine or by any other suitable driving medium. The operating pump 33 will function to draw the operating fluid from the reservoir 32 through the intake pipe 47, and will force the fluid through the supply pipe 45, through the valve ports 39, 42, 41 and 38 into the pipe 57, through the cross connection 56, through the control valves 61, 61, 62 and 63 into the elevating conduits 50 and 51, and through the ports 12' which establish communication between the bores 11, of the cylinders 8 and 9, of respective elevating mechanisms 1, 2, 3 and 4.

When the apparatus is in the inoperative position all of the plungers 17 thereof are positioned against respective partitions 14 at adjacent ends of the pair of cylinders 8 and 9, as shown in Figure 5, of the drawing. When the operating fluid enters the cylinder bores 12 through the port 12' it will act against the plungers 17, thereby forcing the plunger 17, mounted in the cylinder 8, outwardly in one direction, while the plunger 17, mounted in the cylinder 9 will also be forced toward the free end thereof in the opposite direction. Upon movement of the plungers 17, as above stated, the toggle bars 27 and 28, through their connection therewith by the plunger rods 18, guide blocks 19 and bearing pin 29, will be shifted to the vertical position as shown in Figure 4 of the

drawing, whereby they will exert an endwise pressure on the foot 30 and elevate the entire vehicle.

If for any reason the operation of the pump 33 has not been discontinued after the maximum elevation of the device has been reached, the relief valve 48 will function to allow the passage of the operating fluid through the relief pipe 49 back into the intake pipe 47. By this arrangement no damage will result to the mechanism of the device by the continued operation of the pump 33 after the elevating or lowering operation is completed.

After the initial elevating or lowering operation the bores 12 of all of the cylinders 8 and 9 will be completely filled with the operating fluid at all times, and to lower the vehicle after the elevating operation as stated, the valve 34 is regulated to bring the valve ports 41, 42, 43 and 44 into registration with respective valve casing ports 37, 38, 39, and 40, as shown in Figure 2, of the drawing. The operation of the pump 33 will then force the fluid through the lowering conduits 52 and 54, and into all of the cylinders 8 and 9 through the cap apertures 11' in which the various ends of the conduits 52 and 54 connect, as indicated at 53, and 55, respectively.

As the fluid is forced into the cylinders 8 and 9, during the lowering operation through the cap apertures 11' the fluid which was forced into the cylinders 8 and 9 to accomplish the elevating operation, will be forced back through the ports 12' into the elevating conduits 50 and 51, through the valve element ports 38, 42, 41 and 37, into the return pipe 46 and empty into the fluid supply reservoir 32.

During the lowering operation, the plungers 17 of each pair of cylinders 8 and 9, will shift toward each other thereby collapsing toggle bars 27 and 28 against the frame structure of the motor vehicle and elevating the foot 30 carried thereby to the inoperative position as shown in Figure 4, of the drawing.

During the elevating operation the supply fluid would empty from the cylinders 8 and 9 in the reverse direction to that described relatively to the lowering operation, and would be returned to the supply reservoir 32 through the lower conduits 52 and 54.

If the control valves 61 and 65 are open and all other control valves are closed the operation of the device will elevate the vehicle wheel A only. In like manner, if only control valves 60 and 64 are open wheel C would be elevated; if only control valves 63 and 67 are open, wheel B is elevated, and if only control valves 62 and 66 are open wheel D is elevated. By this arrangement the valves 60, 61, 62, 63, 64, 65, 66 and 67 may

be regulated to elevate any of the vehicle wheels A, B, C or D, separately, collectively or in pairs, as required.

From the foregoing description taken in connection with the accompanying drawings, the principle of construction and method of operation will be readily apparent to those skilled in the art to which the invention appertains, and while describing what is now thought to be the best embodiment of the invention it is to be understood that the device shown in the drawings is merely illustrative, and that various changes in the form, proportions and minor details of construction may be resorted to without departing from the principle of the invention, or sacrificing any of the advantages of the invention, which come within the scope of the claims hereunto appended.

20 What I claim is:

1. In a device of the character described, a fluid operated elevating mechanism comprising a pair of horizontally disposed cylinders, a guide member associated with each of said cylinders and extending longitudinally therewith, a plunger slidably mounted in each of said cylinders, a guide block slidably mounted in each of said guide members, a plunger rod connecting said plunger with said guide block, a toggle bar pivotally connected with each of said guide blocks, and a foot pivotally connected to the lower ends of said toggle bars, substantially as described and for the purpose set forth.
2. In a device of the character described, a fluid operated elevating mechanism comprising a pair of horizontally disposed cylinders extending in opposite directions relatively to each other, a guide member rectangular in transverse cross section associated with each of said cylinders and longi-

tudinally aligned therewith, the lower wall of each of said side members formed with a longitudinally extending slot disposed adjacent to the inner side wall of said slot, a plunger slidably mounted in each of said cylinders, a guide block slidably mounted in each of said guide members, plunger rods connecting said plungers with associated guide blocks, a toggle bar pivotally connected to each of said guide blocks and extending through slots, and a foot pivotally carried at the lower end of said toggle bars, substantially as described and for the purpose set forth.

3. In a device of the character described, the combination with a motor vehicle, a fluid operated elevating mechanism attached to the axles of said motor vehicle adjacent to each wheel of the latter, each of said mechanisms including a pair of toggle bars carrying a foot, and power operated means for selectively operating said elevating mechanisms for distending and collapsing said toggle bars, substantially as described and for the purpose set forth.

4. In a device of the character described, the combination with a motor vehicle, a fluid operated elevating mechanism attached to the axles of said motor vehicle adjacent to each wheel of the latter, each of said mechanisms including a pair of toggle bars carrying a foot, power operated means for selectively operating said elevating mechanisms for distending and collapsing said toggle bars, and means for automatically controlling the operation of said power operated means, substantially as described and for the purpose set forth.

In testimony whereof I affix my signature.

ANTON F. NORDENSKJOLD.
